UNITED STATES PATENT OFFICE

NICHOLAS H. STUART, OF BUFFALO, NEW YORK, ASSIGNOR TO REMINGTON RAND INC.,
OF BUFFALO, NEW YORK

LOOSE-LEAF BINDER

Application filed March 13, 1929. Serial No. 346,594.

- The present invention relates to temporary binders and has particular relation to binders of the loose leaf type in which the cover members are adjustable towards and away from one another in order to clamp groups of pages therebetween and to permit of the quick removal of pages therefrom or insertion of additional pages therein.
- 10 One of the objects of the present invention is to provide a binder of the character described having a flexible cover or backing strip for the edges of the pages adjacent to where they are clamped between the covers and which is yieldably connected to one or 15 both of the covers under constant tension regardless of the thickness of the group of pages contained in the binder.

Another object of the invention is to provide a binder of the character described having a flexible backing strip connected to one of the cover members by a spring that is so arranged as to permit of a maximum degree of resilient displacement within a comparatively small space and which permits the backing strip to automatically adapt itself to a wide range of adjustments in the distance between the covers without exceeding the elastic limit of the spring.

20 A further object of the invention is to provide a binder of the character set forth having one of the cover members thereof constructed to form an enclosure for the backing strip and which houses the portion thereof in excess to that actually required to protect the edges of a group of pages of a particular thickness, thus at all times presenting a neat and compact appearance whether the binder is empty or filled to the 25 limit of its capacity.

Other objects of the invention will appear from the following description and appended claims.

- 45 In the accompanying drawings, Fig. 1 is a view of a loose leaf binder constructed in accordance with the invention and with the covers thereof in an open position.
- 50 Fig. 2 is a sectional view through the

binder with the covers thereof in a closed position.

Fig. 3 is a sectional view taken on line 3-3 of Fig. 1.

Referring to the drawings, a loose leaf binder constructed in accordance with the invention is shown as comprising a pair of cover members 1 and 2 each of which embodies a rectangular frame 3 having outwardly tapering margin strips 4 secured to the upper and lower edges thereof as shown in Fig. 1. An inner metallic plate 5 and an outer fiber sheet 6 are secured to the frame 3 and provide a compartment therebetween which houses the adjusting mechanism presently to be described.

The upper and lower edges as shown in Fig. 1 of each of the plates 5 are bent around the frame 3 to form flanges 7 which overhang the frame in spaced relation thereto to provide guideways 8 at opposite sides of cover 1. Spacing members 7 engage between flanges 7 and frame 3 intermediate the ends of the flanges and retain said flanges in proper spaced relation with the frame and form the outer edges of the guideways 8. Channel members 10 are secured to the adjacent edges of the cover members 1 and 2 respectively and are formed with ear portions 11 which are 30 pivotally connected by ears 12 provided on each of a pair of clamping bars 13. These bars are provided with apertures 14 adapted to receive the ends of a pair of studs 15 which are carried by a pair of transfer bars 16. These transfer bars directly engage the opposite sides of a group of pages 17 and are each provided with a pair of posts 18 which extend in opposite directions through a series of registering perforations 19 formed in the pages 17.

An adjusting bar 20 extends across the cover 1 between the plates 5 and 6 and is provided with a plate member 21 formed with an offset central portion providing a guideway for slidably receiving ratchet bar 22 which is secured to the cover 1 between the plates 5 and 6. A pair of flexible straps or thongs 23 are each secured at one end to the adjusting bar 20 by means of a clip 24,

(Fig. 1), and extend through the channel members 10 on the cover 1 through slots 25 provided in the retaining bars 16 and are fixed at their other ends in the channel members 10 carried by the cover 2. The stack or group of pages 17 is preferably recessed transversely as indicated at 26, (Fig. 2), in order to receive the thongs 23 where they cross from cover to cover back of the pages.

The adjusting bar 20 is locked in adjusted position by means of a ratchet 27 which is pivotally mounted on the bar 20 for engagement with the ratchet bar 22 and 15 may be released by means of a handle 28 which extends upwardly through a slot 29 provided in the plate 5. The construction and operation of the ratchet mechanism is more fully described in my copending application Serial No. 346,693 filed March 13, 1929.

A flexible backing strip 30 of leather, fabrikoid or other suitable material is secured along one edge to the cover 2 and extends around the back of the binder and into the guideways 8 provided in the cover 1. A stiffening bar 31 is secured to the other edge of the backing strip 30 and is connected to one end of a stirrup 32 the 30 other end of which is formed with a loop 33 which embraces one leg 34 of a rod or guideway 35. One end of this guideway is bent upon itself and is secured to the plate 20 and the other end is similarly bent to 35 provide a leg 36 which is provided with a stop or abutment 37 adjacent to the end thereof. A compression spring 38 surrounds both of the legs 35 and 36 between the loop 33 of the stirrup 32 and the abutment 37 and tends to yieldably maintain the 40 backing strip 30 in position and to take up any slack that may develop therein.

By means of this construction the backing strip is permitted to move relative to the covers when the binder is opened and closed and is maintained under the same tension irrespective of the thickness of the group of pages contained in the binder. For example, if a group of pages is removed from the binder and the bar 20 is adjusted to a new position to securely clamp the remaining pages in the binder, the backing strip will be yieldably drawn into the cover 1 by reason of its attachment to the 50 bar 20 without subjecting the spring 38 to an undue degree of compression. Thus, it will be seen that the backing strip being yieldably connected to the adjustment bar 20, is movable therewith to all positions 55 that it may be adjusted to on the ratchet bar 22 and at the same time is permitted to move relative to the bar 20 and the cover 1 by reason of its flexible connection thereto.

Furthermore, by reason of the particular configuration of the guideway 34 a rela-

tively long spring capable of a considerable degree of displacement may be employed and at the same time permit the bar 20 to be adjusted to a position relatively close to its inner limit of travel.

The invention may be modified in construction and arrangement without departing from the spirit and scope of the invention as defined in the appended claims.

What is claimed is:

1. A temporary binder comprising in combination a pair of cover members, a cross-bar movably mounted on one of said cover members, binding members connecting said cross-bar to the other of said cover members, a backing strip connected at one edge to said last-mentioned cover member, a guide mounted on said cross-bar, a compression spring mounted on said guide and means connected to the free edge of said cover strip having a portion slidable on said guide and operatively engaging said spring.

2. A temporary binder comprising in combination a pair of cover members, a cross-bar movably mounted on one of said cover members, binding members connecting said cross-bar to the other of said cover members, a backing strip connected at one edge to said last-mentioned cover member, a rod having one end thereof fixed to said cross-bar and the other end thereof return bent and provided with a stop, a link having one end thereof connected to the free edge of said backing strip and the other end thereof provided with a portion for slidable engagement with the main part of said rod, and a compression spring surrounding said rod between said stop and said portion.

3. A temporary binder comprising in combination a pair of cover members, one of said cover members consisting of an open frame, a plate secured to one side of said frame and having the opposite side edges thereof extending around and overhanging the other side of said frame in spaced relation therewith to provide guideways therebetween, a plate secured to said other side of said frame and enclosing said guideways, binding mechanism for adjustably connecting said cover members together, a backing strip connected to one of said cover members and extending into the guideways of the other of said cover members, and means for maintaining said backing strip under tension in all of the adjusted positions of said cover members.

NICHOLAS H. STUART.
